UNITED STATES PATENT OFFICE.

JOSEPH T. MERCIER, OF CHICAGO, ILLINOIS.

VENTILATOR.

1,090,325.

Specification of Letters Patent. Patented Mar. 17, 1914.

Application filed February 15, 1912. Serial No. 677,724.

To all whom it may concern:

Be it known that I, JOSEPH T. MERCIER, a citizen of the United States, residing at Chicago, in the county of Cook and State 5 of Illinois, have invented certain new and useful Improvements in Ventilators, of which the following is a specification.

The present invention relates to a ventilator particularly designed and adapted 10 for use upon traveling conveyances.

The objects of the present invention are to provide a ventilator which is of a cheap, simple and durable construction, and to so arrange the parts thereof that they will act 15 as a preventive to the entrance of cinders and other debris through the openings in the ventilator and into the interior of the conveyance.

A further object of the invention is to 20 provide means for accumulating a mass of air below the ventilator, which can be readily sucked or drawn through the ventilator into the compartment.

The invention further consists in the features of construction and the combination 25 of parts hereinafter described and claimed.

In the drawings, Figure 1 is a vertical section of the ventilator of the present invention, showing it secured in operative position; Fig. 2, a cross-section of the ventilator of the present invention; and Fig. 3, 30 a plan view of the ventilator in operative position.

The present invention relates to a ventilator in the form of a register or grid, which 35 is especially adapted to be placed in the floor of a car body adjacent a heating surface, for the purpose of admitting air from below the heater into the interior of the car.

40 The ventilator of the present invention is not of a formation to draw air into the car body unless suction is applied through some other means to draw the air therethrough. That is, before air in any appreciable amount will pass through the ventilator, the ventilating means at the upper end of the car must be put in operation. It is the intention to draw rather than force the air through the ventilator.

45 The invention in the form illustrated comprises a framework 4, which consists of vertically depending walls 5, terminating in horizontally extending flanges 6, adapted to be secured by any suitable means to a portion of a car body 7.

50 As heretofore stated, the invention is par-

ticularly adapted for use in the flooring of the car, although, obviously, if the requirements justify, it may be placed in other portions of the car, where it could perform its 60 function in substantially the same way. The walls 5 in the form shown are joined together by cross pieces 8 of suitable construction and formation; and extending between the walls 5 is a series of upper slat-like members 9 and lower slat-like members 10. By referring to Fig. 2, it will be seen that each of these slat-like members is spaced apart 65 from one another, providing a series of upper openings or slots 11, and lower openings 70 or slots 12. It will further be seen, from a study of Fig. 2, that the slats 9 and 10 are so arranged with respect to one another as to place the slots 11 and 12 out of alinement with one another. This arrangement is provided to impede or help to prevent the entrance of cinders or other debris through the radiator or grid into the interior of the car. The upper slat-like members 9 are preferably of a concavo-convex formation in 75 cross section, as shown in Fig. 2. This is also for the purpose of assisting in the prevention of the entrance of cinders and other debris into the interior of the car through the register or grid, it being obvious that if 80 said cinders should enter through the openings 12, they would strike the concave surface of the sections 9 and be deflected down and away from the openings 11.

85 Lying below the members 10 and extending between the plates 5 is a plate 13, the plates 5 and 13 being arranged with respect to one another in the construction shown to form an I. The plate 13 serves two functions: First, the cinders and other debris striking 90 against this plate will be stopped and deflected, and thus prevented from entering the openings 12; and, second, the plate 13, in conjunction with the plates 5, forms a three-sided receptacle, which provides a compartment 95 below the register or grid surface, in which air will pack or accumulate, so that it can be readily drawn through the radiator or grid and into the interior of the car. It is obvious that when this device is placed 100 upon a moving body, and the plate 13 is facing in the direction of travel of said body, the air striking the plate 13 will be checked and a certain portion of it will accumulate between the plates 13 and 5, the plates 5 105 serving to prevent the air from spreading sidewise and away from the grid surface.

That is, what may be said to be an accumulated pocket of air will always be present between the plates 13 and 5; and this pocket will provide a constant supply of air, which 5 will be sucked through the grid or register and into the interior of the car. It will be noted that the plate 13 is lying approximately midway of the plates 5. This is so that it will act with equal efficiency which- 10 ever direction the conveyance is moving.

It is an obvious fact that with a swiftly moving conveyance there will be a constant rush of air below the conveyance. If some means are not provided for checking and ac- 15 cumulating this air, it will rush by the ventilating grid or opening and only a small portion of it will be extracted and drawn into the car, since the force of suction tend- 20 ing to draw it inward would have to be stronger than the force tending to draw it past the ventilator.

As will be understood from the foregoing description, there are three means provided in the ventilator of the present invention for 25 preventing the entrance of cinders or other debris through the grid and into the interior of the car: First, said debris will strike the plate 13 and be arrested in its momentum, so that gravity will carry it downward 30 and away from the grid openings; second, said grid openings are placed out of alignment with one another, so that there is no direct entrance from the outside to the inside of the car; and, third, the upper sec-

tions of the grid or opening are of a curved 35 formation, which tends to deflect said debris away from the upper of the openings.

I claim:

1. In a ventilator of the class described, the combination of a frame work comprising 40 two side plates, a series of upper slats and a series of lower slats secured to said plates, said slats being arranged in offset relation to one another, a plate rigidly secured to said side plates at approximately the center 45 thereof, said rigidly secured plate extending outwardly from said slats and from a point immediately below said slats to the outer end of the side plates, substantially as de- scribed.

2. In a ventilator of the class described, the combination of a frame work comprising two side plates, a series of upper slats and a series of lower slats secured to said plates, said slats being arranged in offset relation 55 to one another, the lower of said slats being straight faced and the upper of said slats being of convex formation in cross section, a plate rigidly secured to said side plates at approximately the center thereof, said plate 60 extending outwardly from said slats and from a point immediately below said slats to the lower edge of the side plates, substan- tially as described.

JOSEPH T. MERCIER.
